UNITED STATES PATENT OFFICE.

WILLIAM COCHRAN, OF PATERSON, NEW JERSEY.

METHOD OF REPEATING PUNCHED JACQUARD-PATTERNS.

1,179,699.

Specification of Letters Patent. Patented Apr. 18, 1916.

Application filed May 15, 1912. Serial No. 697,439.

To all whom it may concern:

Be it known that I, WILLIAM COCHRAN, a citizen of the United States, residing at Paterson, in the county of Passaic and 5 State of New Jersey, have invented certain new and useful Improvements in Methods of Repeating Punched Jacquard-Patterns, of which the following is a specification.

This invention relates to the art of repeating the patterns or designs represented by punching jacquard cards. According to the present method of carrying out this operation the cards having the patterns to be repeated, *i. e.*, the master cards are 10 passed through what is known as a repeating machine which is provided with a series of punches and corresponding selecting devices which, according to the selecting action of the said devices, operate to produce in the blank card a set of perforations exactly duplicating in disposition those of the master card. The area or field of that part of the blank which is allotted to the pattern or design is of the same dimensions 15 as the corresponding area or field of the master card; that is to say, if the master card is adapted to a jacquard machine having a given number of rows of needles and a given number of needles to a row the 20 card to be repeated is similarly adapted.

In a weaving establishment it is necessary that the jacquard equipment should include jacquard machines of different capacities, according as different designs to 25 be woven require more or less lifting hooks for the proper manipulations of the warp threads. For instance, there may be a number of machines organized to use cards adapted for eight perforations in a row; others to use cards having ten, twelve or 30 sixteen perforations in a row. As is well known, cards of one of these kinds are not capable of being used in a machine adapted for the use therein of cards of any other of 35 these kinds. Hence, if there is no call for, say, the fabric which is developed by the machines using cards punched with perforations sixteen in a row, but there is an excessive demand for the fabric worked out 40 by a machine of the twelve-in-a-row type, the manufacturer cannot adapt the sixteen-in-a-row machines to the weaving of the excess by placing the twelve-in-a-row cards

therein, but such machines must stand idle, except the slow, tedious and expensive primary procedure of specially punching out the design or pattern on the sixteen-in-a-row cards be resorted to, involving intricate and carefully executed manual and 55 mental operations.

In respect to the foregoing, as will hereinafter appear the present invention involves the accomplishment of a very considerable saving of expense and loss of time by making it possible to repeat a design 60 or pattern worked out on a master card or other piece to a certain width-gage (*i. e.*, a given number of possible perforations to a crosswise row) on blank cards in different width-gages. In addition to this and other 65 advantages which will at once be apparent and appreciated both by the fabric manufacturer and the card cutter, the present invention involves the further advantage that by performing the repeating operation 70 in accordance therewith the number of possible perforations in a crosswise row is practically unlimited, thus removing what has heretofore been the principal obstacle to the increase in the number of operating units 75 (needles and lifting hooks) in the jacquard machine; for the primary card-cutting operation effected in the piano machine is of course confined, in respect to the possible extent of any row punched, within the 80 bounds of the dexterity of the operator in the manipulation of the controlling keys of such a machine.

Proceeding, now, to describe my invention in detail, I have illustrated the same herein 85 in reference to two kinds of repeating operations, to wit, one where the repeated card shows longer rows, and the other where the repeated card shows shorter rows, than the rows of the master card, Figure 1 showing the master card; Fig. 2 a repeated card, reproduced from the master card, having its rows longer than those of the latter; and Fig. 3 a repeated card reproduced from the master card, having its rows shorter than 90 those of the latter.

The card, serving as the master card, shown in Fig. 1 is of the twelve-in-a-row type; that is, its working or punched area or field has a width equivalent to the length 95 of a crosswise row of twelve perforations.

The reading of this card proceeds from the upper right hand corner as a starting point to the lower left hand corner, the several crosswise rows being read in sequence each 5 across the card from the right hand side thereof. It will be understood that the perforations (indicated by circles, *a*) and the blanks (indicated by crosses, *b*) in this card together equal the whole width of warp in 10 the loom, or substantially so, each perforation or blank representing a thread of the warp. According to the present method of repeating from this card as a master card the rows in the repeated card are each for 15 each identical to the corresponding row in the master card: that is, if the first row, for instance, in the master card, reading from right to left, has four perforations, then one blank, then two perforations, then three 20 blanks, then two perforations, the corresponding row in the repeated card would begin, proceed and end in exactly the same way. In short, heretofore the repeating operation has contemplated the placing of 25 the perforations in the repeated card in the same disposition in the field thereof as the corresponding perforations occupy in the field of the master card. And in order to reproduce the design or pattern of the card 30 shown in Fig. 1, for instance, on a card whose punching field or area was equal to sixteen units (perforations or blanks or both) in a row, it was necessary for a card of that field or area to be prepared in a 35 piano machine and then used as a master card in the repeating operation. According to my method this intermediate step, involving original production of a master card in a piano machine, is avoided and the design 40 of one card is worked out on a repeated card of a different punched area or field at one and the same time with the repeating operation. For instance, assume that it is desired to reproduce the design of the twelve- 45 in-a-row card of Fig. 1 on the sixteen-in-a-row card of Fig. 2. A machine is employed having a series of rows of punches and a series of rows of selecting devices respectively controlling the punches. There are at 50 least sixteen punches to a row and twelve selecting devices to a row. The master card has 288 units (perforations and blanks) comprising the complete design or pattern thereon, and the repeated card must have the same. The pattern or design of the master 55 card must begin and end on the repeated card at the extreme right and left, respectively, thereof the same as on the master card. I therefore utilize three rows of 60 punches and four rows of selecting devices, and, proceeding from right to left through each row, I make the first row of (sixteen) punches, subject to the control of, respectively, the twelve selecting devices in the

first row, and four in the second row, of 65 selecting devices; the next row of (sixteen) punches, subject to the control of, respectively, the remaining eight of the second row, and eight of the third row, of selecting devices; and the third row of (sixteen) 70 punches subject to the control of, respectively, the remaining four of the third row, and the twelve of the fourth row, of selecting devices. At each operative stroke of the machine four rows of units of the master 75 card will be covered by the selecting devices to three rows of units perforated simultaneously by the punches in the repeated card. So that it will require six strokes in all to 80 cover the 288 units in each card, to wit, 24 rows of twelve-in-a-row in the master card and 18 rows of sixteen-in-a-row in the repeated card. Again, assume that it is desired to reproduce the design of the twelve-in-a-row card of Fig. 1 on the eight-in-a-row 85 card of Fig. 3. I now utilize three rows of punches and two rows of selecting devices, and, proceeding from right to left, through each row, I connect the first row of punches 90 respectively with the first eight selecting devices in the first row thereof; the second row of punches with the remaining four of the first row, and the first four of the second row, of selecting devices; and the third row of punches with the remaining eight of the 95 second row of selecting devices. At each operative stroke of the machine two rows of units of the master card will be covered by the selecting devices to three rows of units 100 perforated simultaneously by the punches in the repeated card. So that it will require twelve strokes in all to cover the 288 units in each card, 24 rows of twelve-in-a-row in the master card and 36 rows of eight-in-a-row in the repeated card.

105

It will be understood that the perforations in the repeated card occur in the same sequence and spacing in which they read in the master card. For instance, in Fig. 1 the second unit of row 2 being a blank, the 110 fourteenth unit of row 1 in Fig. 2 is a blank; in Fig. 1 the seventh unit in row 3 being a perforation the fifteenth unit in row 2 of Fig. 2 is a perforation.

My invention results in numerous advantages to the weaver as well as to the card cutter other than those herein specifically named and all of which will be at once apparent and appreciated by those skilled in the weaving and card cutting arts once the 115 120 essential feature of the invention, herein fully set forth, is grasped.

Having thus fully described my invention, what I claim and desire to secure by Letters Patent is:

The herein-described method of repeating a punched jacquard pattern which consists in simultaneously punching a group of lines

125

of perforations in a blank jacquard card in the same sequence and spacing in which the perforations read in the pattern, but with each crosswise punching line of said perforations of a different length from that of any crosswise line of perforations in the pattern and with each said line fully occupied by perforations and spacings, or either,

repeated from the pattern, substantially as described. 10

In testimony whereof I affix my signature in presence of two witnesses.

WILLIAM COCHRAN.
